(57) **CLAIM**

The ornamental design for a dispensing device, as shown and described.

DESCRIPTION

FIG. 1 is an isometric view of a top, front, and left side of a first embodiment of a dispensing device of the present invention;

FIG. 2 is a rear elevational view of the dispensing device of FIG. 1

FIG. 3 is a front elevational view of the dispensing device of FIG. 1

FIG. 4 is a right side elevational view of the dispensing device of FIG. 1;

FIG. 5 is a left side elevational view of the dispensing device of FIG. 1;

FIG. 6 is a top plan view of the dispensing device of FIG. 1; FIG. 7 is a bottom elevational view of the dispensing device of FIG. 1;

FIG. 8 is an isometric view of a top, front, and left side of a second embodiment of a dispensing device of the present invention;

FIG. 9 is a rear elevational view of the dispensing device of FIG. 8;

FIG. 10 is a front elevational view of the dispensing device of FIG. 8;

FIG. 11 is a right side elevational view of the dispensing device of FIG. 8;

FIG. 12 is a left side elevational view of the dispensing device of FIG. 8;

FIG. 13 is a top plan view of the dispensing device of FIG. 8; and,

FIG. 14 is a bottom elevational view of the dispensing device of FIG. 8.

The subject matter shown above in dashed lines forms no part of the claimed invention.
